ABSTRACT OF THE DISCLOSURE

An annular cathode which emits a disc-shaped beam of electrons radially inward around its inner periphery, is divided into segments that are mechanically connected and disconnected to provide access to the electron beam focal point.

BACKGROUND OF THE INVENTION

Field of invention

This invention relates to a novel segmented annular cathode structure which emits a disc-like beam of electrons radially inward toward a focal point, the cathode segments being mechanically separable to provide easy access to the cathode work area at the focal point.

Description of the prior art

Conventional methods of producing electron beams liberate electrons from the surface of a heated cathode by thermionic emission. Electron beams may also be produced by non-thermionic annular devices such as a hollow cathode and a contoured cathode.

Electron beams are generated by a hollow cathode by the release of electrons as a result of both surface emission and the impact of high-energy electrons with 40 background gas molecules within the hollow cathode itself. A novel annular hollow cathode is disclosed and claimed in copending application Ser. No. 417,399 Patent No. 3,381,157 entitled "Annular Hollow Cathode Discharge Apparatus," filed Dec. 10, 1964 and assigned to the same assignee.

Contoured cathodes operate in a glow discharge mode in a high pressure region, and produce electron beams by secondary emission processes such as from ions striking its surface. Focusing is accomplished by contouring the 50 surface of the cathode. A novel annular contoured cathode is disclosed and claimed in copending application Ser. No. 666,230 now Patent No. 3,430,091 entitled "Contoured Cathode," filed Aug. 21, 1967 and assigned to the same assignee.

Hollow cathodes comprise closed hollow annular rings fabricated from wire mesh or perforated metal with a circular aperture about its inner periphery. When the cathode is biased to a high negative potential, with respect to its surroundings which act as the anode, a glow discharge is initiated. Under certain combinations of cathode geometry and pressure level, a well-collimated disc-like beam of high-current density, high-energy electrons emanates from the hollow cathode aperture and is focused at the center of the annulus.

The annular hollow cathode and the contoured cathode are used for applications such as welding, brazing, heat treating, zone melting, fiber drawing and vapor deposition. In these applications, utilizing the cathode of unitary structure, access to the workpiece is obtained only through insertion along the axis.

2

SUMMARY OF INVENTION

An object of the invention is to provide a segmented hollow or contoured cathode which is substantially annular in configuration and which may be opened to provide access to the electron beam focal point.

In accordance with the present invention, an improved segmented hollow cathode is provided wherein the cathode structure has at least two segments, mechanically or magnetically connected at their ends to enable the cathode structure to open thereby providing quick access to the electron beam focal point by a path other than through insertion along the axis, as, for example, is essential in order to weld a closed circular ring. Electrons are emitted from the cathode and are accelerated radially inward toward a workpiece held at the focal point. Energies are obtained corresponding approximately to the full voltage applied across the discharge, usually in the kilovolt range.

In a preferred embodiment of the invention, the cathode comprises two symmetrical segments mechanically connected by a simple hinge along their outer periphery. The mating parts on the opposite side of the cathode are provided typically with pin and pilot hole means for easy alignment.

The invention accordingly provides a segmented hollow or contoured cathode that offers access to the work area at its focal point without the necessity of inserting a workpiece along its axis.

The foregoing and other objects, features and advantages of the present invention will become more apparent in the light of the following detailed description of preferred embodiments thereof as illustrated in the accompanying drawings.

BRIEF DESCRIPTION OF THE DRAWINGS

FIGURE 1 is a schematic of a typical annular hollow cathode system and illustrates the cathode as a unitary structure.

FIGURE 2 is an illustration of a preferred embodiment of the segmented annular hollow cathode.

FIGURE 2A is a perspective view of the hinge assembly illustrated in FIGURE 2.

FIGURE 3 is an illustration of another embodiment of the segmented cathode connected by magnetic means.

FIGURE 3A is a sectional view of the cathode and magnetic fastening means illustrated in FIGURE 3.

FIGURE 4 is a perspective view of a segmented hollow cathode system wherein the vacuum chamber has a hinged cover.

DESCRIPTION OF THE PREFERRED EMBODIMENT

This invention will be described by reference to an annular hollow cathode, but it will be apparent to one skilled in the art that a contoured cathode may be used instead.

Referring generally to FIGURE 1, there is shown a unitary hollow cathode beam discharge system, and FIGURE 2 shows the structure of the novel segmented hollow cathode of this invention.

The annular hollow cathode illustrated in FIGURE 1 is described in detail in copending patent application Ser. No. 417,399, now Patent No. 3,381,157.

The annular hollow cathode 20 in FIGURE 1 is fabricated, for example, from stainless steel, from a 10 mil, 40 mesh wire cloth or similar substance. Cathodes thus fabricated have an outer diameter, D_o , typically from 1.3 to 4 times the inner diameter D_i , but are obviously not limited thereto. The height H of the cathode assembly 70 does not appear to be a critical factor; however, the size of the aperture A can be critical as is explained in copending patent application Ser. No. 417,399, now Patent

No. 3,381,157. The wall thickness or mesh size do not have an appreciable affect upon the electron beam output. Also, the hollow, solid-wall cathode structure illustrated in FIGURES 1 through 4 can be a perforated wall configuration, such as the perforated wall configuration illustrated in the above referenced copending application.

In FIGURE 1, the cathode 20, workpiece 22 and associated supports are enclosed in an airtight enclosure 24 which comprises glass or other suitable material. The cathode is supported by arm 26 which is also the negative potential lead to the cathode. Arm 26 may be covered by an insulating material, not shown. Workpiece 22 is held in place by a metallic arm 30 on which are positioned two adjustable clamping structures 28 and 28'. If the workpiece 22 is metallic, it is grounded to act as the anode. If the workpiece 22 is a nonconductor, the workpiece support structures 28, 28' and 30 act as the anode.

The enclosure 24 is initially evacuated by means of vacuum pump 36. After evacuation to the proper pressure level, a supply of gas 38 is used to produce a gas atmosphere within the enclosure. The gas can be air, helium, hydrogen, nitrogen or argon, or any gas suitable for the workpiece.

The theory of operation of the hollow cathode, as presently known, is explained in considerable detail in copending patent application Ser. No. 417,399, now Patent No. 3,381,157. Basically the operation may be compared with the operation of conventional glow discharges. In a conventional glow discharge, practically all of the potential drop across the discharge occurs in a region quite close to the cathode, this drop being known as the cathode fall. The characteristic thickness of the cathode fall depends on the gas pressure, gas type, cathode material and applied voltage. The high potential end of this region can be identified visually by a sharp demarcation between a dark portion of a discharge near the cathode, called the cathode dark space, and a bright region called the negative glow. Equipotential lines for this distribution are parallel with the cathode. As explained in detail in copending patent application Ser. No. 417,399, now Patent No. 3,381,157, the perturbed potential distribution in the vicinity of the aperture A resembles a concave lens. The electric field lines normal to the equipotential lines converge in the vicinity of the aperture. Electrons generated inside the cavity drift toward the aperture in the relatively weak electric field therein. In the aperture region, they are accelerated through the full cathode fall and thus acquire a highly directed velocity approximately along the field lines. In this manner, the perforated wall hollow cathode forms a highly collimated energetic electron beam.

FIGURE 2 is an illustration of the segmented annular hollow cathode of the invention. The cathode 20 is divided into two symmetrical segments 30 and 32. A pin and pilot hole arrangement is provided wherein pins 34 on one end of segment 30 fit into pilot holes 36 on the corresponding end of cathode segment 32. At their opposite ends, cathode segments 30 and 32 have attached hinges 38, 40 respectively. These hinges, when connected by a pin 42, enable the cathode segments 30, 32 to be pivoted open, thereby allowing access to the focus of the electron beam.

FIGURE 2A is a view of the hinge and pin arrangement illustrated in FIGURE 2, and represents only one of many possible mechanical fastening arrangements anticipated by the invention. In addition, it is not essential to divide the cathode into two equal sections. More than two sections of different sizes are possible. As can be seen in FIGURE 2, pivoting of the cathode sections 30 and 32 about their pivot point provided by hinges 38, 40, permits the cathode to be opened, making it possible to easily place workpiece 22 therein.

Of course, segments 30 and 32 can be connected by means of pins 34 and pilot holes 36 on each end thereof, 75

thereby eliminating the hinge. With this arrangement, it is necessary only to pull the two segments apart to gain access to the cathode work area.

The embodiment of FIGURES 3 and 3A illustrates another of the many unlimited possibilities for fastening the cathode segments 30, 32. In this embodiment, small permanent magnets 43 are permanently attached to the ends of each symmetrical segment and when these segments are brought together in proper alignment, the magnets 43 securely hold the segments 30, 32 in a fixed abutting relationship. Of course, there is a possibility of some interaction between stray magnetic fields and the electron beam. Also the magnetic fastening means could be sensitive to temperature.

FIGURE 4 illustrates a typical segmented hollow cathode system and, in general, comprises a sectional vacuum chamber 44, segmented cathode 20 and a workpiece 22. In this embodiment the vacuum chamber 44 has a hinged cover 46 that opens to provide access to the interior of the chamber so that the workpiece 22 can be easily situated therein. The segmented cathode 20 is divided into two segments as described hereinbefore in conjunction with FIGURE 2. The cathode 20 is supported by arm 48 which is also the negative potential lead. The workpiece 22 rests in semicircular depressions 50, 50' in the container 44 and the cover 46 closes and fastens by means of clamps 52, 52'. The rubber gaskets 54, 56 and 56' insure that the container 44 is airtight after the cover 46 has been closed and fastened. Seals 45 and 47 across the ends of workpiece 22 insure that the workpiece is airtight. The chamber is evacuated through pumping line 60 and gas feed line 62 provides means for introducing gas into the chamber as discussed in conjunction with copending patent application Ser. No. 417,399, now Patent No. 3,381,157.

As indicated previously, the contoured cathode described in copending application Ser. No. 508,314 may also be segmented in the manner disclosed herein by those skilled in the art without departing from the scope of this invention. Furthermore, it is apparent that the segmented cathode need not be fully annular, but may be of any closed or partially closed geometry.

It is apparent that shielded annular hollow cathode configurations such as disclosed in copending application Ser. No. 508,201, Patent No. 3,454,812 entitled "Mounting for a Glow Discharge Cathode" and filed Nov. 17, 1965, may also be adapted to be segmented. In a shielded configuration the cathode is surrounded by a conducting or insulating shield spaced a short distance therefrom for the purpose of inhibiting the formation of a plasma adjacent the cathode walls. The cathode may be a perforated or solid wall device. With shielded configurations it is desirable to locate the hinge on the shield and to mount the cathode segment to the shield by well-known techniques. This latter approach is effective to maintain the cathode free from protuberances.

Although the invention has been shown and described with respect to preferred embodiments thereof, it should be understood by those skilled in the art that the foregoing and other changes and omissions in the form and detail thereof may be made therein without departing from the spirit and scope of the invention, which is to be limited and defined only as set forth in the following claims.

Having thus described typical embodiments of the invention, that which is claimed as new and to be secured by Letters Patent of the United States is:

1. A cathode device for producing an electron beam which comprises:
a segmented cathode structure having a substantially closed perimeter, each of the segments comprising a cathode element adapted to emit electrons therefrom toward a focal point,
and connecting means for joining the cathode segments to each other in an abutting relationship, the con-

- necting means being adapted for connection and disconnection to provide access to the electron beam focal point.
2. The cathode device of claim 1 wherein the connecting means is magnetic.
3. The cathode device of claim 1 wherein the connecting means comprises a hinge and pin pivotally connecting adjoining cathode segments along their outer periphery so that they may be pivoted open.
4. A cathode device as in claim 1 wherein the connecting means comprises a pin extending from the end of a first cathode segment and a pilot hole in the adjoining end of a second cathode segment and adapted so that the first and second segments can be connected by the insertion of the pin in the pilot hole.
5. The cathode device of claim 1 wherein the cathode is a hollow cathode.
6. A cathode device as in claim 1 and including a segmented shield surrounding said cathode, said connecting means joining said shield segments in abutting relation.
7. Apparatus as in claim 1 wherein said cathode is a contoured cathode.
8. An apparatus for generating an electron beam which comprises:
- a segmented cathode structure having a substantially closed perimeter, each of the segments comprising a cathode element adapted to emit electrons therefrom toward a focal point;

connecting means for joining the cathode segments to each other in an abutting relationship, the connecting means being adapted for connection and disconnection to provide access to the electron beam focal point;

enclosure means surrounding the cathode structure, the enclosure means providing an access to the cathode structure and having sealing means to produce an airtight seal about the enclosure means; means to produce a vacuum in the enclosure; and means for causing the cathode structure to emit therefrom a plane collimated uninterrupted sheet of electrons.
